(57) CLAIM

The ornamental design for a boot as shown and described.

DESCRIPTION

FIG. 1 is a perspective view of the first embodiment of a boot showing our new design.

FIG. 2 is a left-side elevation view of the first embodiment.

FIG. 3 is right-side elevation view of the first embodiment.

FIG. 4 is a front elevation view of the first embodiment.

FIG. 5 is a rear elevation view of the first embodiment.

FIG. 6 is top elevation view of the first embodiment.

FIG. 7 is perspective view of the second embodiment of a boot showing our new design.

FIG. 8 is a left-side elevation view of the second embodiment.

FIG. 9 is a right-side elevation view of the second embodiment.

FIG. 10 is a front elevational view of the second embodiment.

FIG. 11 is a rear elevation view of the second embodiment; and,

FIG. 12 is a top elevation view of the second embodiment. The broken lines in the drawing represent portions of the boot that form no part of the claim.

1 Claim, 12 Drawing Sheets
